US0D1059969S

(12) **United States Design Patent** (10) Patent No.: **US D1,059,969 S**
(45) Date of Patent: ** Feb. 4, 2025

(54) **GRINDER**

(71) Applicant: **NINGBO CHEFSHERE KITCHEN TECHNOLOGY CO., LTD**, Zhejiang Province (CN)

(72) Inventor: **Guoping Zhang**, Zhejiang Province (CN)

(**) Term: **15 Years**

(21) Appl. No.: **29/897,770**

(22) Filed: **Jul. 19, 2023**

(51) LOC (15) Cl. **07-04**
(52) U.S. Cl. **D7/679**

(58) **Field of Classification Search**

(57) **CLAIM**

The ornamental design for a grinder as shown and described.

DESCRIPTION

FIG. 1 is a front elevational view of a grinder showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines showing portions of the grinder form no part of the claimed design.

1 Claim, 7 Drawing Sheets
